UNITED STATES PATENT OFFICE.

RAYMOND B. GILCHRIST, OF NEWARK, NEW JERSEY, ASSIGNOR TO THE GILCHRIST COMPANY, OF NEWARK, NEW JERSEY, A CORPORATION OF NEW JERSEY.

DRINK MIXER.

Application filed March 22, 1922. Serial No. 345,683.

To all whom it may concern:

Be it known that I, RAYMOND B. GILCHRIST, a citizen of the United States, and a resident of Newark, in the county of Essex and State of New Jersey, have invented certain new and useful Improvements in Drink Mixers, of which the following is a full, clear, and exact description.

The invention relates to drink mixers.

10 In machines for this purpose, the liquid constituents of the drink to be mixed are usually poured into a receptacle which is generally designated a "shaker," from many different containers disposed away from the mixer. The receptacle with these constituents therein is brought to the mixer and placed in operative relation thereto and is removed from the machine after each mixing operation, to discharge its contents. 15 This is rendered necessary, because so many different ingredients and flavors are used in making drinks that they are, in nearly all cases, mixed individually. It is usually necessary to run the agitator for a considerable period to properly blend or mix the constituents and, therefore, it is desirable that provision be made for retaining the receptacle and agitator in operative relation to permit the dispenser to perform other duties 20 during the mixing operation. In drink mixing, it thus becomes necessary to frequently place the receptacle containing the constituents into cooperative relation to the agitator and to withdraw it from the machine 25 to discharge its contents and cleanse the receptacle between mixing operations.

A desideratum in this art is to expedite and simplify the operations necessary to bring the receptacle and agitator into cooperative relation, to maintain them in such relation, in starting and stopping of the motor and the removal of the receptacle. Heretofore, in machines whereof I am aware (excepting those exhibited in concurrently pending applications), it has been necessary in their use to manually manipulate the receptacle into operative position and withdraw it therefrom and to additionally perform some separate step or operation, such as lowering the motor and agitator together, or shifting the agitator and its shaft into the receptacle and relatively to the motor, or raising and locking a receptacle-support to establish and maintain cooperative relation of the receptacle and agitator or to con-

trol the operation of the machine. Another desideratum in this art is to simplify the machine by dispensing with movable connections in and for the driving mechanism for the agitator.

One object of the present invention is to provide an improved drink mixer in which these additional operations or steps are dispensed with and in which manual shift of the receptacle is utilized to completely control the operation of the machine and to secure it and the agitator in cooperative relation. By dispensing with the necessity of these additional steps or operations, the time of the dispenser in performing them is saved and the service is improved.

Other objects of the invention are to provide: a receptacle-controlled machine which is equipped so that the receptacle can be manipulated to control its locking into operative position around the agitator, its release for withdrawal, and the starting and stopping of the motor; a machine of this type in which movable connections in and for the driving mechanism for the agitator are dispensed with; and a machine which is simple in construction, which may be easily and readily operated and which is efficient in operation.

Other objects of the invention will more fully appear from the following description.

The invention consists in the several novel features hereinafter set forth and more particularly defined by claims at the conclusion hereof.

In the drawings: Fig. 1 is a side elevation of a machine embodying the invention. Fig. 2 is a front elevation of the vertical guide. Fig. 3 is a vertical section. Fig. 4 is a section on line 4—4 of Fig. 1.

The invention is exemplified in a machine comprising an electric motor 10 of usual construction, to the rotor of which is secured a pendent shaft 11 with an agitator 12 fixed to its lower end; a hollow supporting standard 13 which is secured to a base 15 by a screw 16, an upper member 17 suitably secured in the member 13, and a bracket 18 suitably secured to the upper end of member 17 to which the motor 10 is suitably secured, as at 19. The electrical connections for supplying energy to the motor 10 comprise a conductor-cord 20 leading through a handle 21 and comprising conductors 22 and 23 connected to the motor normally discon-

2
nected, switch-members 24 and 25 being included in the conductor 23 to control the operation of the motor. The casing of the motor 10 is fixedly secured to the support at 5 19 and the agitator 12 is maintained in substantially relatively fixed vertical relation to the motor.

10 A receptacle 26 having an open top, a closed bottom 27, a lower wear-band 28 and an upper wear-band 29, is adapted to contain the constituents of the drink to be mixed and to be placed into cooperative relation to the agitator from beneath the latter, which is supported sufficiently above the 15 base 15 to permit the insertion and withdrawal of the receptacle.

20 The invention contemplates placement of the receptacle into and out of operative relation to the agitator, locking and unlocking the receptacle and control of the motor by manipulation of the receptacle itself, so that shift of the motor or the agitator are not necessary to bring the agitator into working position in the receptacle. For this purpose, 25 a stationary vertically extending receptacle guide 30 is provided for the back of the receptacle. The guide has its front face curved or arcuate in substantial conformity with the outer periphery of the receptacle so 30 that when the latter is pressed backwardly against the guide, the receptacle will be guided against lateral movement and into its operative position without danger of striking the agitator 12.

35 A lug 31 extending forwardly from a lever 34 projects through and forwardly from the receptacle-guide 30, to serve as a bottom support which is vertically positioned to hold the receptacle in operative position and to 40 act with an upper abutment or hook 33 for locking the receptacle in its operative position around the agitator. Hook 33 is adapted to engage the inner periphery of the receptacle and lock the upper portion of the 45 receptacle against forward movement. Hook 33 is disposed above the bottom support 30 and at the rear of the receptacle, so that the weight of the front portion of the receptacle and the material therein will tend to 50 hold the lower portion of the receptacle in its seat on the lug 31 and against the front of guide 30. Hook 33 is secured by screws 33^a to a strip 13^a and guide 30 is provided with lugs 31^a which are secured to said strip. 55 The latter is secured to the standard 13 by screws 13^b.

60 For the purpose of automatically controlling the operation of the motor by manipulation of the receptacle, a switch-lever 34 has its lower end 35 formed to pivotally fit in the lower end of the standard-member 13 and on the plate 14, is extended through a slot 36 in front of the supporting standard and through a slot 37 formed in guide-member 30 and is provided with a cam-portion

38 which is adapted to be struck by the receptacle 26 while it is being raised into operative position and to be held in shifted position as long as the receptacle is secured in its operative position. A stop-shoulder 70 34' is provided on lever 34 to limit the forward movement of the lever under the influence of spring 43, so it will be normally projected into the path of the receptacle the correct distance to operate the motor-switch. Lever 34 is also formed with a cam 39 in the hollow standard, to shift and control a plunger 40 which is slidably held in the hollow-standard and carries a switch-pin 41 at its upper end which is adapted to bridge the gap between the normally separated switch-members 24 and 25 and close the circuit for the operation of motor 10. Switch-members 24 and 25 are secured to a block 42 of insulating material. Plunger 40 may be 80 formed of insulating material, such as wood, and is normally pressed downwardly by a spring 43 interposed between a shoulder on the plunger and a plate of insulating material 44 suitably held in the upper end of the standard-member 17. A wear-plate 45 is secured to the lower end of plunger 40.

85 The operation of the machine will be as follows: Assuming the parts to be in normal position shown in Fig. 1, the operator will place receptacle 26, containing the constituents of the drink to be mixed, against guide 30 and under the agitator 12, as shown by dotted lines in said figure; will 90 press it rearwardly with sufficient force to cause the guide to laterally control its vertical movement and then lift it. In this manipulation, the upper portion of the receptacle will slide on the front face of guide 30. When the receptacle has been lifted sufficiently, its upper margin will pass into hook 33 and its lower rim will be disposed above the bottom support 31. When the receptacle is released, its lower rim will fall onto support 31 and the receptacle will be 95 thus automatically locked in cooperative relation to the agitator. In its upward movement, the receptacle will engage cam 38 and rock lever 34 about its lower end, so that cam 39 will raise plunger 40, cause pin 41 to bridge the switch-members 24, 25 and close the circuit for the operation of the motor 10 and cause it to rotate the agitator. This occurs preferably before the receptacle reaches its operative position. Hook 33 100 positively holds the upper portion of the vessel, so that it will not be displaced by forward pressure of the switch-lever 34 which is under the influence of spring 43 which tends to hold the switch-lever normally in the position shown in Fig. 2. When the motor has run for the desired period and the mixing operation has been completed, the operator will withdraw the 105 lower portion of receptacle 26 forwardly 110

125

130

- to cause its bottom to clear support 31, whereupon the receptacle will be released for lowering movement. Then, the operator will lower the receptacle and press it 5 backwardly against the guide 30 while it is being lowered. When the receptacle has been lowered sufficiently to clear the agitator 12, it will be withdrawn forwardly away from guide-member 30. While the 10 receptacle is being lowered, switch-lever 34 will be released and pass into its normal position to release plunger 40 and cause it to break the circuit and stop the motor. This occurs preferably after the vessel has been 15 lowered sufficiently to bring the liquid therein below the agitator, so that the latter will run for a sufficient period to discharge the adhering liquid by centrifugal force, into the receptacle.
- 20 The invention exemplifies a drink mixer in which manual placement of the receptacle into operative position causes it to be automatically locked in such position; the placement and removal of the receptacle 25 automatically control the switch for the motor; and in which the bottom-support for the receptacle is pivotally sustained by a member which is swung laterally to control the switch.
- 30 The invention is not to be understood as restricted to the details set forth, since these may be modified within the scope of the appended claims, without departing from the spirit and scope of the invention.
- 35 Having thus described the invention, what I claim as new and desire to secure by Letters Patent, is:
1. In a machine of the character described, the combination of a support, an electric motor fixed to said support, an agitator driven by the motor and stationarily supported from above with sufficient clearance to permit a receptacle with an open top to be placed into its operative position 40 around the agitator, and means for automatically holding the receptacle upon manual manipulation of the receptacle itself into said operative position comprising a bottom-supporting member shiftable laterally by the receptacle.
  2. In a machine of the character described, the combination of a support, an electric motor fixed to said support, an agitator driven by the motor and stationarily supported 45 from above with sufficient clearance to permit a receptacle with an open top to be placed into its operative position around the agitator, and means for automatically holding the receptacle upon manual manipulation of the receptacle itself into said operative position comprising a bottom-supporting member pivoted to swing laterally and shiftable by the receptacle.
  3. In a machine of the character described, 50 the combination of a support, an electric motor fixed to said support, an agitator driven by the motor and stationarily supported from above with sufficient clearance to permit a receptacle with an open top to be placed into its operative position around the agitator, and means for automatically holding the receptacle upon manual manipulation of the receptacle itself into said operative position comprising a bottom-supporting member pivoted to swing laterally and shiftable by the receptacle.
  4. In a machine of the character described, the combination of a support, an electric motor fixed to said support, an agitator driven by the motor and stationarily supported from above with sufficient clearance to permit a receptacle with an open top to be placed into its operative position around the agitator, means for automatically holding the receptacle upon manual manipulation of the receptacle itself into said operative position comprising a bottom-supporting member shiftable by the receptacle, and a switch for controlling the operation of the motor operable by said member. 55
  5. In a machine of the character described, the combination of a support, an electric motor fixed to said support, an agitator driven by the motor and stationarily supported from above with sufficient clearance to permit a receptacle with an open top to be placed into its operative position around the agitator, means for automatically holding the receptacle upon manual manipulation of the receptacle itself into said operative position comprising a bottom-supporting member shiftable by the receptacle, a switch for controlling the operation of the motor, and means shiftable by the receptacle itself to shift the switch before the receptacle reaches its operative position and to keep the motor running while it is in said position. 60
  6. In a machine of the character described, the combination of a motor, a support for the motor, an agitator driven by the motor and supported from above with sufficient clearance to permit a receptacle with an open top to be placed into operative position around the agitator while the latter is in said position, means to slidably guide the upper portion of the receptacle while it is being manually shifted into its operative position, and a pivoted element provided with a support on which the bottom of the receptacle may be manually placed, arranged to swing laterally. 65
  7. In a machine of the character described, the combination of a motor, a support for the motor, an agitator driven by the motor and supported from above with sufficient clearance to permit a receptacle with an open top to be placed into operative position around the agitator while the latter is in said position. 70

tion, means to slidably guide the manually shifted receptacle into its operative position, a laterally swinging element provided with means on which the bottom of the receptacle 5 may be manually placed and held, and a switch for controlling the motor operable by said element.

8. In a machine of the character described, the combination of a motor, a support for 10 the motor, an agitator driven by the motor and supported from above with sufficient clearance to permit a receptacle with an open top to be placed into operative position around the agitator while the latter is 15 in said position, a laterally swinging pivoted member shiftable by the receptacle itself provided with a bottom support on which the receptacle will rest when it is manually placed in its operative position, and a sta- 20 tionary coacting member for holding the upper portion of the receptacle.

9. In a machine of the character described, the combination of a motor, a support for 25 the motor, an agitator driven by the motor and supported from above with sufficient clearance to permit a receptacle with an open top to be placed into operative position around the agitator while the latter is in said position, a laterally swinging pivoted 30 member provided with a bottom support on which the receptacle will rest when it is manually placed in its operative position, and a coacting member for holding the upper portion of the receptacle, said upper member 35 and bottom support being retained against substantial vertical movement.

10. In a machine of the character described, the combination of a motor, a support 40 for the motor, an agitator driven by the motor and supported from above with sufficient clearance to permit a receptacle with an open top to be placed into operative position around the agitator while the latter is in said position, a laterally swinging pivoted 45 member provided with a bottom support on which the receptacle will rest when it is manually placed in its operative position, a coacting member extending into and for holding the upper portion of the receptacle, and a switch for controlling the motor 50 operable by said pivoted member.

11. In a machine of the character described, the combination of a motor, a support 55 for the motor, an agitator driven by the motor and supported from above with sufficient clearance to permit a receptacle with an open top to be placed into operative position around the agitator while the latter is in said position, a laterally swinging pivoted 60 member provided with a bottom support on which the receptacle will rest when it is manually placed in its operative position.

tion, a coacting member for holding the upper portion of the receptacle, and means to slidably guide the upper portion of the receptacle to said upper member. 65

12. In a machine of the character described, the combination of a motor, a support for the motor, an agitator driven by the motor and supported from above with sufficient clearance to permit a receptacle with an open top to be placed into operative position around the agitator while the latter is in said position, a pivoted member provided with a bottom support on which the receptacle will rest in its operative position, and a hook for engaging the inner periphery of the upper portion of the receptacle, said support and hook being normally retained in position to hold the receptacle in its operative position. 70 75 80

13. In a drink mixer of the class described, the combination of a supporting standard, a motor supported at the upper end of said standard, a spindle connected with the motor armature and extending vertically downwardly in front of said standard, a mixing button at the end of said spindle, a lever structure pivoted at its inner end inside of said standard below said button and terminating in front of said standard in a shelf for receiving a container, a clip at the upper end of said standard for receiving the entrance edge of a container, an abutment on said lever structure, and circuit controlling springs inside of said standard in the path of said abutment to be controlled to close the motor circuit when a container is placed on said shelf. 85 90 95

14. In a drink mixer of the class described, the combination of a supporting standard, a motor supported at the upper end of said standard, a spindle connected with the motor armature and extending vertically downwardly in front of said standard and terminating in a mixing button, a lever structure pivoted at its rear end on said standard and terminating in front of said standard in a horizontal shelf for receiving a container, a circuit for said motor, and circuiting controlling contacts in the path of said lever to be actuated to close the circuit when a container is applied on the shelf, means normally holding said lever structure away from said contacts whereby said circuit is normally opened, and means at the upper end of said standard for engaging with the upper edge of a container to cooperate with said shelf to suspend the container on said standard. 100 105 110 115 120

Signed at Newark, N. J., this 11th day of February, 1922.

RAYMOND B. GILCHRIST.
